UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

MACHINE FOR RENDERING SOLES FLEXIBLE.

1,126,350.

Specification of Letters Patent.

Patented Jan. 26, 1915.

Application filed December 5, 1912. Serial No. 735,060.

To all whom it may concern:

Be it known that I, ARTHUR BATES, a subject of the King of Great Britain, residing at Leicester, in the county of Leicester, England, have invented certain new and useful Improvements in Machines for Rendering Soles Flexible; and I do hereby declare the following to be a full, clear, and exact description of the invention, such as will enable others skilled in the art to which it appertains to make and use the same.

This invention relates to sole flexing machines and more particularly to such machines of the type wherein the flexibility of the sole is obtained by making a series of slashes or cuts in one face of the forepart of the sole. In one type of machine, heretofore proposed, for flexing soles in this manner a single knife is provided for making a succession of parallel slashes, the knife being of a width not greater than the length of the shortest slash required, slashes of increased length being produced by moving the knife laterally in the line of cut. In practising this method a majority of the slashes require two cutting movements of the knife and consequently the feed of the sole through the machine is somewhat delayed.

The object of the present invention is to produce a machine of the type described in which the speed at which the sole is fed through the machine is increased, and is undelayed by the operation of the mechanism for operating the slash forming means.

In accordance with this object, one feature of the invention contemplates the provision of a plurality of reciprocating slash forming knives, arranged to overlap one another, and means to vary the extent of their overlapping relation, as the sole is fed through the machine, to produce slashes of varying length as required by the width of the portion of the sole being operated on at each incision. With this construction a feed step may be taken after each single incising movement of the knives. Preferably the overlapping knives are spaced apart a distance equal to the length of feed step used.

Thus, after a feed step has taken place, the slash made by one knife will be brought into alignment with another knife so that during the succeeding incising movement the said slash will be given a proper increase of length. This construction permits the slashing to take place while the machine is run at

a high rate of speed. To further increase the speed of the machine the knives are employed as the sole feeding agent. In the preferred construction, the slashing knives are arranged to enter the sole at an oblique angle to its face, thus producing a series of overlapping, thin sole portions which, when the sole is bent, will easily pick up or open after the manner of fish scales and thus impart extreme flexibility to the sole. The direction of opening of the slashes, that is, toward the toe or toward the heel, is of importance to different manufacturers. Some manufacturers use an insole tack pulling machine in which the tool has a tack engaging movement from the toe toward the heel, while other manufacturers use a tack pulling machine in which the tool has a reverse movement. In order to prevent injury to the sole, by an engagement of the tack pulling tool in the slashes, the slashes should open in the same direction as the direction of movement of the tool.

Another object of the invention, therefore, is to provide for the production of oblique slashes opening either toward the toe or toward the heel of the sole.

In accordance with this object a further feature of the invention contemplates a construction and arrangement of the parts whereby a sole may be instantly presented to the slashing means either toe first or heel first while the direction of feed remains the same. No claim is made broadly to provision, in a machine of the type described, for producing oblique slashes opening either toward the toe or heel of the sole, but the inventor believes himself to be the first to produce a machine by which this result may be obtained without making any alteration in the working parts of the machine.

Other features of the invention relate to certain devices, combinations and arrangements of parts, hereinafter described and claimed, which possess advantages in simplicity of construction and ease of operation which will be apparent to those skilled in the art.

The preferred embodiment of the invention is illustrated in the accompanying drawings in which:

Figure 1 is a plan of the machine with a portion of the frame removed to show the parts beneath it; Fig. 2 is a rear elevation, partly in section, showing the mecha-

nism inside the frame; Fig. 3 is a side elevation, partly in section, showing the mechanism within the frame; Fig. 4 is a detail view of the slides for supporting the slashing knives and the means for moving said slides laterally; and Fig. 5 is a detail view, partly in section, of the floating carrier, for the sole slashing knives, and its operating mechanism.

In the embodiment of the invention illustrated in the drawings the machine is shown as comprising a box-shaped frame 1, within which the mechanism is situated, the upper portion of the said frame forming a table 2 over which the sole passes. A slot 3 is formed in this table through which reciprocating knives 4, 5 operate. These knives enter the sole at an oblique angle to its face and are situated one behind the other, as shown, for a purpose which will be described later. Situated above the said slot is a bridge 6, suitably secured to the frame 1, for receiving the thrust of the knives. The bridge 6 is provided with a renewable wear plate 7 held in place by a guide pin 7^a and bolt 7^b (see Fig. 3). Against the bridge 6 the sole, in the particular construction shown, is intermittently pressed by a presser foot 8. The knives 4, 5 for producing the slash in the sole have imparted to them a four-way motion so as first to slash the sole then to feed the sole then to retire from the sole and finally to move back to their starting position. In order to enable this motion to be imparted the knives are carried on a floating frame 9 which is controlled by two inovable pivots 10 and 11. The pivot 10 is supported and actuated by one end of a supporting and driving link 12, the other end of which is provided with a sleeve embracing an eccentric 13 on the main shaft 14 of the machine. The pivot 11 is carried by one arm 15 of a bell-crank lever pivoted to the frame of the machine at 17, the other arm 18 of the said bell-crank lever being provided with contact faces engaging a cam 19 on the main shaft 14 of the machine. The eccentric 13 and the cam 19 are so arranged that in the operation of the machine the eccentric will cause the knife-carrying frame 9 to rock on its pivot 11 to force the knives into the sole to cut parallel slashes. After these slashes have been formed and while the knives lie therein the cam will come into operation and swing the bell-crank lever arm 15 in the direction of the arrow (Fig. 3), and thereby cause the knife-carrying frame 9 to swing on its pivot 10 and thus feed the sole forwardly, or to the left of an observer of Fig. 3. In the next portion of the cycle of operations the eccentric 13 will come into action to withdraw the knives from the sole and when this has taken place the cam 19 will swing the bell-

crank lever arm 15 in the reverse direction and thus cause the knife-carrying frame 9 to move back again on its pivot 10 to its original position. A spring 20, one end of which is attached to the bell-crank lever 18 and the other end to the frame 1 of the machine (see Fig. 3) is provided in order to counter-balance the weight of the moving parts.

The presser foot 8 is formed on a bell-crank lever having arms 21, 22 and is held in contact with the work during the slashing operation by means of a spring 23 which surrounds a spindle 24 pivoted by means of a stud 25 to the arm 21. The spindle 24 passes through the frame of the machine and is provided with a milled headed nut, as shown, for the purpose of adjusting the presser foot toward or from the sole and consequently varying the pressure of the presser foot thereon. In order to release the presser foot from the work and thus allow it to be fed by the knives 4, 5 the arm 22 is provided with a cam roll 26 which is adapted to be engaged by a cam 27 on the shaft 14. As will readily be understood, when the cam 27 comes into operation the bell-crank lever will be swung on its pivot 17 and thus move the presser foot, against the action of its spring, from the work.

As the width of a sole varies at different parts, means is provided to enable the length of the slash to be varied correspondingly as the slashing progresses along the length of the sole and preferably this means is controlled by one or more devices which bear on the edge of the sole. As previously pointed out, the knives 4, 5 are mounted one behind the other, and the width of each of the knives is equal to the shortest slash which it is required to cut. In order to increase the length of the cut means is provided whereby the knives may be moved relatively to each other laterally so that as the knife 5 forms a slash of its width during one stroke, at the next slashing stroke the knife 4, which is situated at one side of it, will cut partly into the slash which the knife 5 previously made and will also by reason of its lateral displacement, cut more or less to one side of the said slash but in alinement therewith, thereby increasing its length. In order to carry this into effect the two knives 4, 5 are fixed on independent slides 28, 29 mounted on the knife-carrying frame 9 so that when the said slides are operated by mechanism which will now be described, the said knives will be moved laterally relatively to each other. The slides 28-29 work in a suitable slideway 30 on the knife-carrying frame 9, and are held in place therein by a plate 31 secured to the said frame by screws. As shown in Fig. 3 the plate 31 is provided with an undercut portion 32 which fits over pro-

jecting portions formed on the slides. The slides 28, 29 are in alinement with one another but the slide 28 is made thicker than the slide 29, as shown in Fig. 4, so that the knife 4 projects beyond and overlaps the knife 5. In their extreme inward position when the shortest slash is required, that is, a slash which is equal in length only the width of one of the knives, they will lie directly over each other. In order to move the slides 28, 29 they are provided with slots 33, 34 and these slots are engaged by blocks 35 pivoted on levers 36 that are fulcrumed to the frame of the machine at 37. The levers 36 are provided at their upper ends with gages 38 that are adapted to contact one on either side of the edges of a sole as it is passed through the machine, a spring 39, one end of which is attached to one of the levers 36 and the other end to the other lever, being provided so as to keep the two gages 38 in contact with the edge of the sole.

From the foregoing it will be understood that as the sole is fed through the machine the edge gages bearing on the edge of the sole at points between which the knives are acting, will move the knives 4, 5 and decrease or increase the overlap of the knives according to the width of the sole, or the width of the portion of the sole to be slashed, so that the slashes cut will correspondingly be varied in length. It will of course be understood that the length of feed step is equal to the distance between the two knives so that the knife 4 will come into its correct position in alinement with the slash previously caused by the knife 5. In order that the distance between the two knives shall be equal to the length of feed step this distance may be varied by inserting packing pieces between the knives to bring the edges of the knives nearer to or farther from each other.

In order to vary the depth of cut of the knives 4, 5 they are fixed in the slides 28, 29 so that they can be adjusted upwardly and downwardly, slots 40, 41 being provided in the shanks of the knives for this purpose through which pass suitable locking screws (see Fig. 1) which take into the slides. Two screws 42, 43 are provided which project from the lower portion of the knife carrying frame 9 and act as abutment screws to take the thrust of the knives.

It will be clear that when the knives 4, 5 are in the sole that the edge gage levers 36, owing to their operative connection to the knives, will be unable to expand and hence the sole cannot be fed through the machine if its taper is an increasing one. In order to overcome this difficulty the edge gages 38 are mounted in hollow bosses 44 formed on the ends of the levers 36 and are provided with springs 45 which surround reduced portions 46 of the gages and hold them yield-

ingly in position. The reduced portions pass through the bosses 44 and are provided with nuts 44^a so that the outward position of the gages can be varied. It will be understood that when the levers are held stationary, as aforesaid, the gages will yield to allow for the increased width of the sole as it is fed forward. These springs are arranged to be stronger than the spring 39 so that they will not come into play except during the time when the knives are actually in the sole, as it will be understood that as soon as the knives come out of the sole the yielding contact points will be able to take up their correct positions. The slots 33, 34 engaged by the blocks 35 lie in the general direction of the feed so as to allow the feed movement of the knives.

The machine is provided with fast and loose pulleys 47, 48 and with any convenient clutch mechanism and starting mechanism.

A part 49 of the frame of the machine is pivoted to the main portion of the frame by means of a spindle 50 to which it is fulcrumed, the said spindle passing through a boss 51 on the main portion of the frame and having a spring 52 surrounding it, which is held in place by means of a nut and washer, as shown. The part 49 can be swung backwardly about its fulcrum, a handle 53 being provided for this purpose, in order to render the various parts inside the frame accessible. The spring 52 will hold the part 49 locked, whether it is swung backwardly in the manner just described, or whether it rests in the position shown in Fig. 3.

The operation of the machine will no doubt be understood from the foregoing, but it may be briefly re-stated as follows: The presser foot 8 is depressed by means of a treadle (not shown) connected to its arm 22, and the sole having been placed on the work table and inserted between the bridge 6 and the presser foot, so as to grip the work, and the edge gages 38 having been placed in contact with the edge of the sole, the machine is started. The knives 4, 5, through the mechanism just described, will then move forward and slash the sole. They will then move forward in a direction to the left of an observer of Fig. 3 to feed the sole and then come out of the work and return to their original position. During the next slashing stroke of the knives the knife 4 will come into line with the slash previously formed by the knife 5 and will, if the contour of the sole is such as to cause the edge gages 38 to move it, be displaced more or less to one side of the slash and consequently during this slashing movement of the knife 4 the length of the slash will be increased to accord with the width of the sole at this point. The cutting operations just described are repeated re-

quired number of times whereby a series of slashes of the proper varying lengths are obtained.

It will be understood that by having both 5 knives movable they are guided into their correct position on the sole by the gages 38, and, when operating on an insole, both knives being always located the correct distance from the channel as it is important 10 that the slash should not extend across the channel.

Instead of two knives being used as shown, three or more could be employed, the said knives being slidingly connected 15 one to the other, and the outside knives being connected in the manner hereinbefore described to the levers 36.

It will be observed that the bridge 6 is so constructed and arranged as to provide 20 an unobstructed space at either side of the slashing knives. As a result of this construction a sole may be instantly inserted between the knives and bridge either toe first or heel first, thus producing slashes 25 opening toward the toe or heel, respectively, as may be desired, without change in the direction of feed, readjustment of gaging devices or in fact any alteration whatever in the machine. It is only necessary for the 30 operative, if the toe of the sole is first presented to the knives, to initially position it so that the first slash will be at the toe width corresponding to the width of the knife 4, and if the heel of the sole is pre- 35 sented first, to initially position it so that the first slash will be at the shank width corresponding to the width of the knife 4.

While the machine is capable of operating on any type of sole, it is especially 40 adapted to flexing welt insoles wherein the slashes extend between the portions of the channel cut at each side of the sole, that is, the construction provides for an unslashed margin on the sole, thus preserving the 45 channel lip and between substance from mutilation.

While it is preferred to employ the specific construction and arrangement of parts shown and described, since this construction 50 and arrangement is the simplest and most efficient embodiment of the invention which has yet been devised, it will be understood that this construction and arrangement is not essential except so far as it is specified 55 in the claims, and may be varied or modified without departing from the broader features of the invention.

What is claimed as new, is:—

1. A shoe sole slashing machine, having, 60 in combination, a plurality of parallel slashing knives, of less number than the number of slashes to be cut, spaced apart a distance equal to the desired spacing of the slashes, means for relatively moving the knives and 65 sole and for reciprocating the knives toward

and from the sole to cause a succession of parallel slashes to be cut in the sole, and means for causing a slash made by one knife on one reciprocation to be lengthened by the next adjacent knife on the succeeding reciprocation, substantially as described. 70

2. A shoe sole slashing machine, having, in combination, means for feeding a sole step-by-step, means for cutting a transverse slash in the sole after one sole feeding movement, 75 and means for lengthening the slash so made after the next succeeding sole feeding movement, substantially as described.

3. A shoe sole slashing machine, having, in combination, a plurality of sole slashing 80 knives, means to feed the sole step-by-step, means for reciprocating said knives toward and from the sole, to cut a plurality of slashes, after each sole feeding movement, and means for lengthening the slash made by 85 one of said knives by the cutting stroke of a different knife after each succeeding sole feeding movement, substantially as described.

4. A shoe sole slashing machine, having, in combination, two parallel sole slashing knives, means for reciprocating the knives toward and from the sole and for feeding the sole step-by-step, and means for causing one of said knives to lengthen the last preceding 90 slash, and the other knife to cut a new slash after each sole feeding step, substantially as described.

5. A shoe sole slashing machine, having, in combination, at least two parallel slashing 100 knives, and means for moving said knives relatively to each other laterally to vary the outer limits of the slashed area, substantially as described.

6. A shoe sole slashing machine, having, 105 in combination, at least two parallel slashing knives, and means controlled by the contour of the sole area to be slashed for moving said knives relatively to each other laterally to vary the outer limits of the slashed area, 110 substantially as described.

7. A shoe sole slashing machine, having, in combination, at least two parallel slashing knives, means for moving said knives relatively to each other laterally, and means engaging the sole edge for controlling the extent of said lateral movement, substantially 115 as described.

8. A shoe sole slashing machine, having, in combination, at least two parallel slashing 120 knives spaced apart a distance equal to the desired spacing of the slashes, means to vary the lateral relation of said knives, and means for feeding the sole step-by-step a distance at each step equal to the spacing of the 125 knives, whereby the slash made by one knife will be completed by another knife, substantially as described.

9. A shoe sole slashing machine, having, in combination, at least two parallel slash- 130

ing knives relatively movable laterally, devices, engaging the sole edge, connected to said knives for controlling the amount of said lateral movement, means for feeding the sole past said devices, and means for rendering said devices ineffective during the feeding movement, substantially as described.

10. A shoe sole slashing machine, having, in combination, at least two parallel slashing knives, means for reciprocating the knives toward and from the sole and for feeding the sole while the knives are engaged therein, means for moving said knives relatively to each other laterally, and means for preventing the operation of said last named means until the withdrawal of the knives from the sole, substantially as described.
15. 11. A shoe sole slashing machine, having, in combination, at least two parallel slashing knives, a carrier for said knives, mechanism for actuating said carrier to reciprocate the knives toward and from the sole and to advance said knives while engaged in the sole to feed it, and devices controlled by the contour of the sole area to be slashed for moving said knives relatively to each other laterally constructed and arranged to 25 be inoperative while the knives are in the sole, substantially as described.

20. 12. A shoe sole slashing machine, having, in combination, at least two parallel slashing knives, a carrier for said knives, mechanism for actuating said carrier to reciprocate the knives toward and from the sole and to advance said knives while engaged in the sole to feed it, devices controlled by the contour of the sole area to be slashed for 25 moving said knives relatively to each other laterally, and yielding members engaging the sole edge, carried by said devices for rendering said devices ineffective while the knives are in the sole, substantially as described.

30. 13. A shoe sole slashing machine, having, in combination, a sole slashing knife, a floating carrier for said knife, means to reciprocate said carrier and its knife toward and from the sole, a support to receive the thrust of the carrier and its knife, means to advance the knife while in the sole to feed it, and an intermittently operating presser foot to hold the sole on said support during the 35 slashing stroke of the knife, substantially as described.

40. 14. A shoe sole slashing machine, having,

in combination, a sole slashing knife, a carrier for said knife, and means for actuating said carrier to force the knife into the sole, 60 then advance the knife to feed the sole and then withdraw the knife from the sole and reposition it for another parallel slash, substantially as described.

45. 15. In a sole slashing machine, a unitary four-motion sole slashing and sole feeding device, and means for operating it to produce parallel slashes in the sole, substantially as described.

50. 16. A shoe sole slashing machine, having, in combination, sole slashing means, means to reciprocate said slashing means in a path oblique to the sole face, a support to receive the thrust of the slashing means, means for feeding the sole step-by-step between the 75 sole slashing strokes of said slashing means, and provision for instantly inserting the sole between said slashing means and support in proper position to receive the first cut either toe first or heel first, whereby slashes opening toward either the toe or heel are produced at the will of the operative, substantially as described.

55. 17. A shoe sole slashing machine, having, in combination, sole slashing means, means to reciprocate said slashing means in a path oblique to the sole face, means for feeding the sole step-by-step between the sole slashing strokes of said slashing means, and a bridge opposite the slashing means to receive 90 the thrust thereof, having an unobstructed space at each side of the slashing means whereby a sole may be instantly initially positioned to receive the first slash in either the toe or shank at the will of the operative, substantially as described.

60. 18. A shoe sole slashing machine, having, in combination, a unitary means for producing in one face of a sole a succession of oblique slashes opening toward one end of the 100 sole and invariably feeding the sole step-by-step in one direction, and means for receiving the thrust of the slashing means permitting an instant reverse presentation of the sole to the slashing means in proper initial position to produce slashes opening toward the other end of the sole while feeding in the same direction, substantially as described.

ARTHUR BATES.
